UNITED STATES PATENT OFFICE

HULDA M. SCHWEER, OF NEW YORK, N. Y.

DESIGN FOR A TEXTILE FABRIC OR SIMILAR ARTICLE OF MANUFACTURE

Application filed August 16, 1930. Serial No. 36,690. Term of patent 7 years.

To all whom it may concern:

Be it known that I, HULDA M. SCHWEER, a citizen of the United States, residing at New York City, in the county of New York and State of New York, have invented a new, original, and ornamental Design for a Textile Fabric or Similar Article of Manufacture, of which the following is a specification, reference being had to the accompanying drawing, forming part thereof.

The drawing is a face view of a piece of textile fabric showing my design, a repeat unit of which is contained between the rectangle outlined by dot and dash lines. Such unit is repeated over the surface of the fabric as indicated by the dot and dash line extensions beyond the unit area.

I claim:

The ornamental design for a textile fabric or similar article of manufacture as shown and described.

HULDA M. SCHWEER.
